UNITED STATES PATENT OFFICE.

PHILIP BENVISSUTO AND LEUIGI MOMBARUZZO, OF NEW YORK, N. Y.

AUTOMATIC GAS-CONTROL VALVE.

Application filed October 30, 1920. Serial No. 420,802.

To all whom it may concern:

Be it known that we, PHILIP BENVISSUTO and LEUIGI MOMBARUZZO, subjects of the King of Italy, and residents of 65 Bank 5 Street, New York, in the county of New York and State of New York, have invented certain new and useful Improvement in Automatic Gas-Control Valves, of which the following is a specification.

10 This invention relates to automatic pressure control devices.

Its primary object is to provide a simple, effective and easily operable device of this kind which may be readily applied at the 15 termination of one, or between two conduits conveying gaseous or liquid media.

Another important object of our device is to provide means whereby parts thereof may be regulated so as to check the flow of such 20 media entirely, or permit them to either freely pass through the conduits or through automatic pressure controlling means.

The above and further objects will be more fully apparent from the following description and the accompanying drawings, forming part of this specification, in which:

Fig. 1 is an elevation of a preferred form of my device.

Fig. 2 is a longitudinal cross sectional 30 view therethrough taken on line 2—2 of Fig. 3.

Fig. 3 is a transverse cross sectional view taken on line 3—3 of Fig. 2.

Fig. 4 is a similar view taken on line 4—4 35 of Fig. 2, with the cut-off member removed.

Figs. 5 and 6 are cross sectional views similar to that shown in Fig. 3.

Fig. 7 is an enlarged cross sectional view taken on line 7—7 of Fig. 5.

40 Fig. 8 is a similar cross sectional view taken on line 8—8 of Fig. 6.

Fig. 9 represents a cross sectional view similar to Fig. 2 of a modified form of our device.

45 Fig. 10 illustrates another modification of our device.

Referring to the drawings, 10 represents a preferably cylindrical housing made in a convenient form to be readily attached to

50 one or more conduits for conveying gaseous or liquid media.

Within its cylindrical body a wall or bottom 11 is shown which is provided with one larger opening 12 and a smaller opening 13 (see Fig. 4) the centers of which lie at a circular distance on a circle indicated at 14.

Rotatably mounted within the housing and revolving upon wall 11 is a cylindrical cut-off member 15 provided with a uniform longitudinal bore 16 and another bore 17 which is reduced at its lower portion. These bores are disposed diametrically opposite each other, and their centers lay on a circle of the same diameter as that of circle 14.

65 The housing 10 is provided with a slot, which may either be straight, as seen at 18, or inclined as shown at 18' and which is provided with three notches 19, 19' and 19''.

Fastened in the body of cut-off 15 is a 70 handle 20 which protrudes through slots 18, and which may be kept in any of the three positions by means of the notches, as will be explained later.

Within bore 17 is provided a valve 21 75 comprising a substantially cylindrical hollow body with a conical seat which registers with aperture 13. Valve 21 glidably fits the lower, reduced bore portion, while it leaves a free space around its outer surface when elevated into the upper, enlarged bore portion.

By means of handle 20, cylinder 15 may be turned within the housing, to three different positions as has been said above.

85 When in the position shown in Figs. 2 and 3 bore 17 registers with aperture 13 while aperture 12 is closed by the cut-off body.

In Figs. 5 and 7 another position is shown 90 where bore 16 registers with aperture 12, while aperture 13 is closed.

To close both apertures, cylinder 15 is positioned in the manner illustrated in Figs. 6 and 8.

95 When applied in connection with a conduit, for instance a gas line, our device may be attached near or at the end of a burner.

100 For use during hours when the light may be readily watched the cylinder 15 is turned in position illustrated in Figs. 5 and 7, per-

mitting the free flow of gas through aperture 12 and bore 16.

During night time, and particularly when only a small flame is to burn, cylinder 15 is 5 turned in position of Figs. 2 and 3. By so doing valve 21, now within the reduced portion of bore 17, is caused to glide upon wall or bottom 11 of the housing, and before it reaches a position perpendicular above aperture 13, gas is permitted to enter 10 through the latter into bore 17 and under the valve, which is forced upward into the enlarged bore portion, as indicated in broken lines in Fig. 2.

15 When in this position, the valve is held suspended by the flow of gas as long as the gas pressure is sufficient to overcome the atmospheric pressure plus the weight of the valve.

20 When the gas pressure ceases, however, or is lowered so that it can not keep the valve afloat, the latter will gradually sink down to a position shown in Fig. 2 in full lines.

At the moment the conical seat of the 25 valve engages the small aperture 13, the gas flow is entirely stopped.

When now the gas pressure is again increased to normal, the valve will not be lifted, since the gas pressure upon the small 30 valve seat area is smaller than the atmospheric pressure upon the enlarged area of the upper valve body.

In order to again permit the flow of gas through bore 17, the valve has to be first 35 unseated by other force than that of the gas pressure. This is accomplished by moving cylinder 15 to another position, for instance that shown in Figs. 5 and 7 or 6 and 8, whereby the valve is forced to leave aperture 13. Then the cylinder is turned to 40 position of Fig. 3, and the valve will be again caused to float in the manner described before.

In the first eight figures our device is 45 designed for use in vertical position. It becomes desirable, however, to adapt it for use also in a horizontal position, where the gravity action of the valve can not be utilized. For this reason we have provided 50 a spring 22 (Fig. 9) designed to form an equivalent therefor.

The operation of this modified form of 55 our device is the same as that described in connection with the vertically attached mechanism.

Another, much simplified form is shown in Fig. 10.

Here a gas pipe 23 is illustrated to which a conventional gas cock 24 is attached, at 60 the upper end of which a gas nipple 25 is secured. Forced into the latter's widest portion, at the inner end of the threads, is a disk 26, provided with a central aperture 27. Before pressing in plate or disk 26, 65 a valve 28 is inserted into reduced portion

29 of the nipple. This valve is similarly constructed as is valve 21, but it may be provided with outer, longitudinal grooves to permit the passage of gas when the valve floats. For limiting the upward movement 70 of the valve and to prevent its jamming in the upper, smallest nipple portion which receives tip 30, a pin 31 or other suitable means are provided.

The operation of the valve is the same as 75 that in the first mentioned design, with the difference that when the valve is to be unseated it is necessary to slightly knock at the nipple. By so doing, gas is admitted through aperture 27 under valve 28 which 80 is forced upward.

It is also obvious that our invention shall not be limited in its application to illuminating gas only, but may be used with conduits for any kind of gaseous or liquid 85 media where such an automatic pressure control may be applicable.

Having thus described our invention, we claim:

1. In a new article of manufacture, comprising in combination a hollow casing provided with a bottom having one smaller and one larger opening, a cylindrical body tightly fitting in said casing and rotatably mounted therein and having two longitudinal bores disposed diametrically opposite each other, one of which being of uniform diameter over its entire length, the other reduced at its lower portion, a hollow valve member fitting in the latter bore, means 90 for turning said body into three different positions, one being that where said first mentioned bore registers with said larger opening, the other where said reduced bore registers with said smaller opening, and the third where neither of the bores register with any one of the openings, and means 95 for keeping said body in any one of these positions at will.

2. In a new article of manufacture, comprising in combination, a hollow cylindrical member having a transverse separating wall provided with two openings, a cylinder fitting in said member and having two diametrically opposite bores, means for turning said cylinder, a hollow cylindrical valve provided in one of said bores, said bores adapted to register with one of said openings at the time, when the said cylinder is turned to desired position.

3. A safety device for automatically closing a supply passage, which comprises in combination, a housing provided with a transverse wall having two apertures, a cylindrical cut-off member turnably mounted in said housing and provided with two diametrically opposite disposed bores, said bores adapted to singly register with one of said apertures at the time when said member is turned into desired positions,

said member adapted to close simultaneously both apertures when in another position, a cylindrical hollow valve provided in one of the said bores and adapted to normally facilitate free communication from one of the apertures, through the bore containing the valve, and to close said aper-

ture when the pressure below the valve is reduced.

Signed at New York, in the county of 10
New York, and State of New York, this
19th day of October, A. D. 1920.

PHILIP BENVISSUTO.
LEUIGI MOMBARUZZO.
